Toro Manufacturing Corporation of Minnesota,
Minneapolis, Minn., a corporation of Minnesota

Application October 23, 1952, Serial No. 21,957

Term of patent 14 years

(Cl. D40—1)

To all whom it may concern:

Be it known, that I, Charles W. Butler, a citizen of the United States of America, residing at Englewood, county of Bergen, New Jersey, have invented a new, original, and ornamental Design for a Lawn Mower, of which the following is a specification, reference being made to the accompanying drawing, forming a part thereof, and in which:

Fig. 1 is a front perspective view of a lawn mower viewed from the right hand side, showing my new design.

Fig. 2 is a front view in perspective of the lawn mower viewed from the left hand side thereof; and

Fig. 3 is a rear view in perspective of the lawn mower.

The characteristic feature of the design is that shown in solid lines.

I claim:

The ornamental design for a lawn mower, as shown and described.

CHARLES W. BUTLER.
